UNITED STATES PATENT OFFICE.

HENRY J. MARTIN, OF BROOKLYN, NEW YORK, ASSIGNOR TO THE REECE BUTTON HOLE MACHINE COMPANY, OF BOSTON, MASSACHUSETTS, A CORPORATION OF MAINE.

NEEDLE-SETTING DEVICE.

1,071,249.

Specification of Letters Patent. Patented Aug. 26, 1913.

Application filed July 5, 1912. Serial No. 707,923.

To all whom it may concern:

Be it known that I, HENRY J. MARTIN, a citizen of the United States, residing at Brooklyn, in the county of Kings and State 5 of New York, have invented certain new and useful Improvements in Needle-Setting Devices, of which the following is a specification, reference being had therein to the accompanying drawing.

10 My invention relates to needle setting devices for sewing machines, and is adaptable to sewing machines of any class or description.

15 The principal object hereof is to provide for the ready and accurate setting of the needle in proper position by the means hereinafter referred to, which may be originally adjusted or standardized, whereby in the subsequent insertion of needles they will in- 20 variably be brought to the predetermined position. This object is accomplished herein by providing at the operating end of the needle bar or carrier a part which is adjustable along the needle bar and has means 25 for holding it to the bar in its adjusted or standardized position, together with a means independent thereof for detachably securing a needle in a given position with relation to said part.

30 I will first describe one form of the device embodying the present invention, and will thereafter point out the novel features in the claims.

35 In the accompanying drawings forming a part hereof, Figure 1 is a side elevation of one form of embodiment of the present invention, showing a portion of a needle bar of a convenient type with the improvement hereof located at the foot of said bar. Fig. 40 2 is a horizontal cross-section on the plane 2—2 of Fig. 1. Fig. 3 is a front elevation of the particular parts involved in this invention, detached from the needle bar proper. Fig. 4 is a vertical central section 45 of the same parts that are shown in Fig. 3 taken on the plane 4—4 of Fig. 2.

Similar letters of reference designate corresponding parts in the several figures of the drawings.

50 A is a convenient form of needle bar. A

detachable block B is shown as connected to the needle bar in a non-adjustable manner so as to substantially constitute a part of the needle bar, and it will be so considered herein.

55

C is a needle of a convenient type.

According to this invention a special part is provided which is adjustable along the needle bar and has means for holding it in adjusted position. This adjustable part D, 60 while it may take various physical forms, is shown as an internal part or plug. Referring to its further details, the part D is shown cylindrical in form and arranged lengthwise within the needle bar or the part 65 B of said bar, so as to be longitudinally movable, and the needle bar is internally bored to receive the part D and permit its movement.

The part D being adjustable along the 70 needle bar, means for holding it in adjusted position are provided in the form of a holding screw E passing from the exterior of the bar into engagement with the plug. For convenience I prefer that the threaded stem 75 of the holding screw E be engaged within a threaded recess in the plug D as shown, so as to move therewith, the movement in that case being permitted by slotting the side wall of the bar at F, this forming a recess for 80 giving the screw E longitudinal play. In the figures the plug D is shown as adjusted to an intermediate position and there secured.

Within the interior longitudinal bore of 85 the needle bar is fitted the needle C substantially in alignment with the plug D. When the needle is set into position by being forced up through its bore to the position indicated in Fig. 4, it will contact with the plug D and thereupon the securing screw G will be tightened for securing the needle in a given relation to the plug, that is to say in abutment or contact with it. It is obvious that with such an arrangement the constructor or mechanic has merely to apply a standard needle to the device while the screw E is loosened and plug D is loose, then carefully adjust the needle in exact and proper relation to coöperate with the remainder of the 90 95 100

sewing mechanism, then tighten the screw G to secure the needle in place, then cause or allow the plug D to descend into intimate contact with the butt end of the needle, and finally securely and permanently tighten the holding screw E, whereby the position of the plug thus carefully predetermined will be maintained so that every succeeding needle will be readily and accurately set in exact position.

It will be noted that as disclosed in the drawings, the needle securing means or screw G is independent of the plug holding means or screw E, so that when detaching and attaching needles, the plug will not be interfered with.

The means of positioning and holding to the needle bar A the detachable portion B thereof, forms no part of the present invention and need not be further described herein than to refer to the leftward extending boss or projection H from the portion B which passes through a corresponding aperture in the left side of the needle bar as indicated in dotted lines Fig. 2, the boss being interiorly threaded and engaged by a headed screw I which when tightened into place, permanently holds the portion B within the recessed lower portion of the bar A.

It is obvious that many of the illustrated features herein may be varied within the scope of the present invention, and I therefore do not wish to be limited to any features or details except as set forth in the appended claims.

The block D is shown slightly greater in diameter than the needle and thereby it may not drop out of the needle bar because too large for the portion of the interior bore 49 which the needle engages.

What I claim and desire to secure by Letters Patent is:

1. A sewing machine needle setting device comprising in combination with the needle carrier, a needle stop consisting of an internal plug freely slidable longitudinally within an internal bore in line with the needle, and adapted to be locked and unlocked therein, a movable lock device 50 adapted for locking said stop in adjusted position, and a needle securing device for detachably securing a needle in the position determined by said stop's adjustment.

2. A sewing machine needle setting device comprising in combination with the needle carrier, a needle stop adjustable longitudinally of the needle and carrier, a set screw operative after adjustment of such stop and accessible from the outside for 60 locking the stop in adjusted position, and a needle securing device for detachably securing a needle in the position determined by said stop's adjustment.

3. A sewing machine needle setting device comprising in combination with the needle carrier, a needle stop adjustable longitudinally of the needle and carrier, a shiftable-position stop securing device operative after adjustment of such stop for locking the stop in adjusted position, and a needle securing device for detachably securing a needle in abutting contact with said stop.

4. A sewing machine needle setting device comprising in combination with the needle carrier, a needle stop adjustable longitudinally of the needle and carrier, a shiftable-position screw-threaded stop securing device arranged on the needle bar and operative after adjustment of such stop 80 for locking the stop in adjusted position, and a needle securing device for detachably securing a needle in abutting contact with said stop.

5. A sewing machine needle setting device 85 comprising in combination with the needle carrier or bar, a needle stop adjustable longitudinally of the needle and carrier, an exteriorly accessible locking device operative after adjustment of such stop for locking 90 the stop in adjusted position, and a needle securing device for detachably securing a needle in the position determined by said stop's adjustment.

6. A sewing machine needle setting device 95 comprising in combination with the needle carrier or bar, a needle stop adjustable longitudinally of the needle and carrier, and freely slidable longitudinally relatively thereto while in engagement with the carrier, an exteriorly accessible locking device operative after adjustment of such stop for locking the stop in adjusted position, and a needle securing device for detachably securing a needle in the position determined 105 by said stop's adjustment, with the needle butt in contact with said stop.

7. A sewing machine needle setting device comprising in combination with the needle bar, a needle stop adjustable longitudinally 110 of the needle and bar, said stop consisting of an internal plug freely movable within an internal bore in line with the needle, a set screw operative after adjustment of such stop, said set screw carried by said stop and 115 accessible from the outside for adjusting and for locking the stop in adjusted position, and a needle securing device for detachably securing a needle in the position determined by said stop's adjustment.

8. A sewing machine needle setting device comprising in combination with the needle bar, a needle stop consisting of an internal plug freely slidable longitudinally within an internal bore in line with the needle, and adapted to be locked and unlocked therein, a 120

movable lock device adapted for, and carried by said stop but operatively movable relatively to said stop for, locking said stop in adjusted position, and a needle securing device for detachably securing a needle in the position determined by said stop's adjustment.

In testimony whereof I affix my signature in presence of two witnesses.

HENRY J. MARTIN.
